TOY DUMP WAGONS

Cyril Gazdarica, near Tilley, Alberta, Canada
Filed June 6, 1968, Ser. No. 734,959
Int. Cl. B60p 1/14

U.S. CL. 298—19

6 Claims

ABSTRACT OF THE DISCLOSURE

A toy wagon is provided that is equipped with a dump body and a variety of kinds of machinery and machine elements such as hinges, pivots, latches, levers, springs, connecting rods, windlasses, detents and castor wheels so that a child using the toy dump wagon will become familiar with various kinds of machinery.

My invention relates to improvements in toy dump wagons.

An important object of my invention is to provide a toy dump wagon which may be pulled either by a handle bar or by a hitch connectible to a child's vehicle such as a tricycle, and which, with or without the just mentioned pulling equipment, may be pushed from the back of the toy wagon.

Another important object of my invention is the provision of a toy dump wagon which during use educates a child in the construction and operation of a variety of kinds of machinery and machine elements, such as hinges, pivots, latches, levers, springs, connecting rods, windlasses, detents and castor wheels.

My invention also aims to provide a toy wagon with a box that may be hoisted and dumped by means of lifting mechanism, that may be held in a desired elevated position by ratchet means and that may be lowered by releasing the ratchet means and backing off on the lifting mechanism.

Other objects and advantages of my invention will become apparent during the course of the following detailed description taken in connection with the accompanying drawing forming a part of this specification, and in which drawing,

FIG. 1 is a top plan view of my top dump wagon, a part being broken away to show concealed mechanism.

FIG. 2 is a view of my toy dump wagon, partly in side elevation and partly in central vertical longitudinal section.

FIG. 3 is a right side elevational view of my toy dump wagon, parts being broken away to show concealed mechanism.

FIG. 4 is a fragmentary view partly in side elevation and partly in longitudinal vertical section showing hitch means connected between the wagon front end and the back of a tricycle.

FIG. 5 is a fragmentary view in side elevation showing a modified form of support for my toy dump wagon.

In the drawing which, for the purpose of illustration, shows a preferred embodiment of the invention, and wherein similar reference characters denote corresponding parts throughout the views, the numeral 5 generally designates my toy wagon including a frame 6 having a rectangular rear end portion 7 of a suitable length and width and a U-shaped front end portion 8 of a lesser width than the width of the rear end portion 7 of the frame 6, and disposed symmetrically of the longitudinal center of the frame 6. Fixedly mounted on the rear end portion 7 of the frame 6 is a platform 9 which is supported along with the rear end portion 7 of the frame 6 by two spaced ground wheels 10, 11 that rotate on an axle 12 affixed transversely below the rear end portion 7 of the frame 6, as by bracket means 13. Pivottally connected below the

2

front end portion 8 of the frame 6, as by a bolt 14, is a swivel fork 15 having its forked end 16 mounted on a front ground wheel 17, as by an axle pin 18 and having a normally forwardly extending shank end 19 to which is pivotally secured, as by a crosspin 20, a pull rod 21 terminating at its normally forward end in a D-shaped handle 22. Pivoted at its rear end portion 23 to the after end of the platform 9 as by suitable bracket means 24 for swinging movement between a position of rest on the platform 9 and an elevated and dumping position is a box 25 provided at its open rear end with a tailgate 26 that is pivoted at the upper rear end of the box, as by a hinge 27. Pivottally mounted at the lower rear end portion of box 25, as by a bracket 28, is a latch 29 swingable between angularly spaced positions in one of which positions, as shown in FIG. 2, the latch 29 engages the lower edge of the tailgate 26 or a relatively short bar 30 at the lower edge of the tailgate 26 to hold the tailgate 26 closed and in the other spaced position, shown in FIG. 3, the latch 29 releases the tailgate 26 and permits it to open by gravity when the box 25 is elevated to its dumping position. Affixed for pivotal swinging movement at the lower forward end portion of the box, as by a bracket 31, is a tailgate control lever 32 that is pivotally connected to the tailgate latch 29 by a link 33 of any suitable rigid material such as heavy wire. Affixed longitudinally and centrally of the rear end portion 7 of the frame 6 is a track 34 which may consist of spaced parallel confronting channel irons 35, 36 providing a way within which a reciprocable member 37 may roll or slide. Connected to the reciprocably mounted member 37 is one end 38 of a contractile coil spring 39 having its other end 40 connected to the rear end portion 7 of the frame 6 so as to urge the member 37 rearwardly along the track 34. Pivotally connected to the member 37 is one end of a rigid bar 41 having its other end pivotally connected to the lower forward end of the box 25, as by bracket 42. Also connected to the reciprocable member 37 is one end of a rope 43 having its opposite end portion coiled onto the reel 44 of a windlass 45 that has its shaft 46 journaled transversely of the front end portion 8 of the frame 6. The windlass 45 includes a crank 47 as well as a ratchet wheel 48 fastened on the shaft 46 and a releasable detent 49 mounted on the side of the frame 6 as by a pivot 50. The sides of the box 25 have rearwardly and downwardly inclined upper edge portions 51, 52 located over the rear ground wheels 10, 11 providing better handholds for a person pushing the wagon from the back.

Referring now to FIG. 4, instead of using the pull rod 21 shown in FIGS. 1-3, I may provide a drawbar 53 having its rear end pivoted to the castor wheel swivel fork shank 19, as by a crosspin 54, and having a forward end portion attached, as by a bolt 55, to the rear bar 56 that extends between the back wheels of a conventional tricycle 57.

In the use and operation of the top dump wagon, clockwise rotation of the windlass crank 47 winds rope 43 onto the reel 44 thereby drawing the reciprocably mounted member 37 forwardly along the track 34 against the tension and resistance of the contractile coil spring 39. This forward movement of the member 37 carries with it the rigid bar 41 which elevates the forward end of the box 25 toward and into the dumping position shown in FIG. 3. Clockwise swinging of the tailgate control lever 32 releases the link 33 permitting the tailgate latch 29 to retract and the tailgate to open by gravity. Release of the windlass detent 49 and counterclockwise rotation of the windlass crank 47 permits paying out of the rope 43 and rearward movement of the reciprocable member 37 under the influence of the contractile coil spring 39 thereby resulting in lowering of the box 25.

Instead of supporting my toy dump wagon directly on the axle 12, I may attach leaf springs such as the spring 58 shown in FIG. 5, for pivotally connecting the forward end of the spring to the underside of the frame 6 as by a bracket 59 and connecting the afterend of the spring to the frame 6 by shackle-links such as the shackle link 60.

Various changes may be made in the form of invention herein shown and described without departing from the spirit of the invention.

I claim:

1. A toy wagon comprising a frame having a front end portion and a rear end portion, ground wheels supporting the rear end portion of the frame, at least one ground wheel pivotally supporting the front end portion of the frame, a box having a front end portion and a rear end portion, said box having its rear end portion pivoted to the rear end portion of the frame for swinging between a position of rest on the frame and an elevated dumping position, a track fixed longitudinally of the frame, said track including a pair of opposed channel members, a member guided for movement along the track, a rigid link having one end pivoted to said member and another end pivoted to the front end portion of the box, a tension spring connected between one end of said track and one end of said member for urging the member in one direction along the track, a line connected to said member, a windlass mounted at the front end portion of the frame adapted to reel in said line and thereby draw said member along the track and to pay out said line to allow reverse movement of said member under the influence of said spring.

2. A toy wagon as defined in claim 1 in which the rear end portion of said box is provided with a tailgate pivotally mounted for swinging between open and closed positions, a latch pivotally movable between latched and unlatched positions relative to said tailgate in its closed posi-

tion, a tailgate control lever pivotally mounted at the forward end portion of said box, and a link between the lever and latch, said lever being movable between spaced positions in which said latch is disposed in its latched and unlatched positions respectively.

3. A toy wagon as defined in claim 1 in which the windlass is provided with a ratchet and a detent releasably engageable with the ratchet.

4. A toy wagon as defined in claim 1 in which the front ground wheel is a castor mounted in a swivel fork.

5. A toy wagon as defined in claim 1 in which the box and the rear end portion of the frame are rectangular and of approximately the same length and width, and the front end portion of the frame is of a lesser width than and extends forwardly of the box.

6. A toy wagon as defined in claim 2 in which the box and the rear end portion of the frame are rectangular and of approximately the same length and width, and the front end portion of the frame is of a lesser width than and extends forwardly of the box.
